UNITED STATES PATENT OFFICE.

CHARLES L. KELLER, OF CINCINNATI, OHIO, ASSIGNOR, BY MESNE ASSIGNMENTS, TO THE FLINTKOTE COMPANY, OF BOSTON, MASSACHUSETTS, A CORPORATION OF MASSACHUSETTS.

SLATE-SURFACING MACHINE AND PROCESS.

Application filed November 30, 1923. Serial No. 677,643.

My invention relates to processes and machines for surfacing shingles with slates of different colors in such a way as to give an effect when laid on the roof of irregular 5 coloring without pattern.

One of the defects of variegated roofs in the past has been that when laid there has been a more or less definable pattern of stripes or blotches, which do not appeal to 10 the eye in a sufficiently subdued manner, to be pleasing as a roof. One of the objects of my invention is to avoid this by placing wavy lines of different colored slate on the roofing, thereby providing a sheet from 15 which individual shingles can be cut, none of which have the same pattern, and in which when laid, the roof will not present any tendency toward definite pattern. It is also my object to provide for interspaced 20 lines of wavy nature on the roofing, intermediate which the colors are formed from a mixture of the several colors at each side thereof.

Another object of my invention is to utilize that process in the production of the roofing which facilitates to the greatest extent the production of the type desired with the minimum of mechanism, and expense, and to this end it has been my object to design a mechanism whereby the mixture of 25 colors lying between the lines of definite color, may be provided with a minimum of labor and machine expense.

The above objects and advantages I accomplish by that certain construction and arrangement of parts to be hereinafter more specifically pointed out and claimed.

In the drawing:

Figure 1 is a perspective detail partially 40 diagrammatic of the machine employed by me.

Figure 2 is a diagram showing the operation of the process and the nature of the resultant shingles.

Referring first to the machine, which exemplifies my process, it will be noted that I show a sheet 1 of prepared roofing felt, which it will be understood travels continuously through the machine. This sheet 45 is surfaced with a bituminous coating, prior to passing through the machine. I show a fixed hopper 2 formed of a series of compartments 3 into which compartments, slate

55 granules or other colored mineral matter is continuously supplied from the storage bins. Each compartment will ordinarily be supplied with a different color from the one next to it, the number of colors being regulated by the number of color tones desired in the final product. 60

The compartments 3 have outlet orifices or ports 4, which, as shown, are preferably of confined width as compared to the width of the compartments.

Beneath the fixed compartments is a movable hopper 5 formed of a series of compartments 6, having relatively narrow ports 7, as compared with the width of the hopper 5, but long enough in the direction of its length to accommodate the flow of slate 70 delivered to it from the hopper 2. This hopper 5 may be mounted by means of brackets 8, upon a pair of supporting rods 9 so that it may be moved to and fro across the sheet of roofing. The limit of movement 75 will be such, ordinarily, that the compartment beneath each port of the fixed hopper will never move out of range of the granules dropping continuously from such port.

The movable hopper may be moved by 80 hand, although I show a mechanism for accomplishing the movement in the shape of a driven shaft 10, having a drum 11 thereon, which drum has a wave line slot 12 therein. The hopper has a finger 13 which engages in 85 said slot, so that as the finger follows the slot, the hopper will be moved to and fro on its supporting rods.

It should be noted that space is left between the ports in the respective compartments of the movable hopper, so that the result of the action of feeding slate through the two hoppers, and moving the roofing sheet beneath the lower hopper will be to form lines of desired width and of wavy 95 outline along the sheet of material, with uncovered spaces of like outline between them.

In the diagram (Figure 2) these wavy 100 lines of colored particles, (shaded for green and brown respectively, as an illustration) are shown at 14 and 15, with intermediate spaces 16. It will also be noted that if one could scrape away the granules along a selected zone lengthwise of the sheet at any point, that both colors of slate would be ac-

cumulated. The width of the lines of colors and of intervening spaces will naturally be regulated by the desire for given effects in the resultant product.

- 5 I utilize the fact of the lengthwise overlapping of the color zones on the partially covered sheet in my process and machine. Thus I preferably regulate the progress of the sheet and the size of the several ports 10 so that an excess of granules is dropped onto the sheet beneath the hopper 5. I then pass the sheet around a roll 17, and then back again over a roll 18, the roll 17 acting to press down the granules against the coating 15 on the sheet.

As an excess is dropped on the sheet a large quantity of granules will drop off of the roofing sheet over the back of the roll 17. I place a hopper 19 where it will catch this excess of granules, and provide this hopper with a long slot or port therein, entirely across the sheet.

The wavy lines of excess covered nature thus deposit in the hopper 19, a mixture of 25 colors of granules and these granules are sprinkled onto the sheet of material before it passes under the roll 17. This excess hopper device is also of value in covering with a solid color in regular practice.

- 30 All of the uncovered areas, resulting from the first wavy line sprinkling are thus covered over with a slate which consists of a mixture of the granules deposited from the wavy lines at each side of the lines of solid 35 color, and furthermore this mixture of colors is deposited all over the sheet and some of it will remain on the solid colored areas, toning them down so as to result in a sheet in which sharp definitions between color zones 40 are not apparent, and in which unpleasantly striking effects are avoided.

In cutting up the resultant sheet, dependent upon the width of the color zones, and the width of the sheet, the final shingles will 45 be of different nature. There will not be any regularity of color outline, however, and no general tendency of stripes exhibited in the final roof. The illustrated cut by the dotted lines 20 of Figure 2, shows one form 50 of possible subdivision.

Where the desire is for relatively narrow bands of color and wide bands of mixed color, it may be necessary to supplement the feed back action described in order to 55 give sufficient covering in the intermediate zones. This can be done by shoveling or feeding into the hopper 19, a sufficient quantity of granules formed from a mixture of the several colors used in the first two hoppers. So far as process is concerned, the 60 hoppers for deposit of primary colors could be in two or more units or the streams could be crosswise instead of lengthwise of the sheet.

Having thus described my invention,

what I claim as new and desire to secure by Letters Patent, is:—

1. A method of making mineral covered prepared roofing, which consists in feeding a mastic coated sheet beneath a series of interspaced streams of differently colored mineral granules, and subsequently feeding the sheet beneath a stream of a mixture of said granules. 70

2. A method of making mineral covered prepared roofing, which consists in feeding a mastic coated sheet beneath a series of interspaced oscillating streams of differently colored mineral granules, and subsequently feeding the sheet beneath a stream of a mixture of said granule. 75 80

3. A method of making mineral covered prepared roofing, which consists in feeding a mastic coated sheet beneath a series of interspaced oscillating streams of differently colored mineral granules, then inverting the sheet while feeding it, and imposing the excess deposited by the above noted streams back again on the sheet to cover the areas intermediate the said streams. 85 90

4. A method of making mineral covered prepared roofing, which consists in feeding a mastic coated sheet beneath a series of interspaced oscillating streams of differently colored mineral granules, and subsequently feeding the sheet beneath a stream of a mixture of said granules, and then dividing the sheet crosswise and lengthwise into a series of roofing units. 95

5. A machine for making mineral covered prepared roofing, which comprises a compartment hopper continuously pouring a series of streams of relatively different colored mineral granules toward a continuously moving mastic coated sheet, another compartment hopper between said streams and the sheet, said second hopper being movable to catch the streams and deposit them in interspaced wavy lines upon the sheet, and additional means for subsequently covering the interlying spaces with a mixture of the differently colored granules. 100 105 110

6. In a machine for the purposes described, means for selectively feeding in interspaced streams excess quantities of differently colored granules onto a moving web, means for removing said excess, and means for refeeding said excess onto said moving web. 115

7. A machine for the purpose described, comprising a hopper into which is to be poured a series of streams of differently colored mineral granules, said hopper being formed with compartments one for each color, ports in said hoppers to deposit the streams upon a traveling web of roofing material, said hopper being movably mounted so as to be oscillated crosswise of the sheet, and mechanical means for oscillating said hopper adapted to time the move- 120 125

ment of the hopper so as to produce a wavy line on the travelling web.
8. A machine for the purpose described, comprising a hopper into which is to be poured a series of streams of differently colored mineral granules, said hopper being formed with compartments one for each color, ports in said hoppers to deposit the streams upon a traveling web of roofing material, said hopper being movably mounted so as to be oscillated crosswise of the sheet, means for accomplishing an inversion of the roofing sheet, and a hopper located below the inverted sheet to catch the excess granules falling from the sheet upon inversion and located over the non-

inverted portion of the sheet so as to re-deposit the granules upon the sheet.

9. A machine for the purpose described, comprising a hopper located so as to deposit a mineral granular substance upon a moving sheet of prepared roofing material, a pair of rolls, the lower in advance of the upper, over which the said sheet moves after passing the said hopper, and an additional hopper located beneath the upper roll and over the roofing sheet behind the lower roll to catch excess granules falling from the inverted sheet and re-deposit them upon the said sheet prior to its contact with the said lower roll. ²⁰ ²⁵ ³⁰
